UNITED STATES PATENT OFFICE.

JOHN FISCHER, OF LOUISVILLE, KENTUCKY.

HARNESS-SADDLE.

SPECIFICATION forming part of Letters Patent No. 392,020, dated October 30, 1888.

Application filed February 28, 1888. Serial No. 265,510. (No model.)

To all whom it may concern:

Be it known that I, JOHN FISCHER, of Louisville, in the county of Jefferson and State of Kentucky, have invented certain new and useful Improvements in Harness-Saddles; and I do hereby declare the following to be a full, clear, and exact description of the invention, such as will enable others skilled in the art to which it pertains to make and use it, reference being had to the accompanying drawings, which form part of this specification.

My invention relates to an improvement in harness-saddles; and it consists in, first, the combination of a continuous flap or strap which extends entirely across the back of the animal, with suitable metallic plates which are placed inside of the strap and provided with perforations to receive the staples which secure the supporting-straps in position, the terrets, and the screws which pass through the flap and the plates; second, the combination of the hook, which has its rear portion to extend across under the flap or strap, and provided with two sets of screw-holes, with the saddle-piece which extends across the top of the strap, the screws which are passed through the center of the pad and through the flap and enter the body of the hook, all of which will be more fully described hereinafter.

The object of my invention is to produce a harness-saddle without a tree, and which is flexible at its center, so as to adapt itself to the shape of the animal's back; to form the flap of one continuous piece, which extends entirely across the animal's back, and to stiffen it upon each side of the center by means of a metallic plate, and to prevent the screws which secure the two parts of the hook in position upon the saddle from becoming unscrewed.

Figure 1 is a side elevation of a harness-saddle embodying my invention. Fig. 2 is a vertical section of the same. Fig. 3 is a transverse section taken through the hook and the saddle.

A represents the flap or strap, which extends entirely across the animal's back, and which forms the body of the saddle, to which all of the other parts are secured. This flap may either be made of one continuous piece or it may be formed of two pieces, which may be spliced together for the sake of economy in

leather, and which spliced piece will be hidden either by the saddle seat or by a jockey-flap, if one is used. To the ends of this flap straps are secured, and to these straps the girth or belly-band will be buckled in the usual manner.

The saddle is made of a double thickness of material at its center by being provided with a lining, which consists of a single thickness of leather or other material, and upon each side of the center of the saddle inside of the flap is placed a metallic perforated plate, C, which is suitably bent and provided with series of perforations, through which the staples, 65 clamping-screw, and the terrets freely pass. The upper ends of these plates approach just sufficiently near to opposite sides or edges of the bridle-hook to leave the saddle perfectly flexible at its center, so that it can be made to 70 freely adjust itself to the shape of the animal's back. Through the flap upon each side of the center and through the metallic plates placed in the flap are passed the staples D, which have suitable shoulders, bearings, or stops, 75 formed thereon so as to bear solidly against the outer side of the flap, and which staples have their prongs to pass through the flap and the metallic plates, and are clinched on the under side of the flap, as shown in Fig. 2. 80 The supporting-straps G are fastened by suitable rings, H, in these staples, these staples being rigidly secured in position upon the flap by means of the metallic plate placed therein. The harness is adapted to be used for any purposes that may be desired, as the supporting-straps will bear any kind of weight which may be applied to them.

The terrets I pass down through the flaps and the metallic plates placed therein, and have their lower ends to screw into the metallic screw-threaded plates J, secured inside of the upper part of the pad L. Also, passing down through the flap and the metallic plates placed therin, and the threaded metallic plates secured to the inner side of the upper part of the pad, are the clamping-screws N and the terrets, and these clamping-screws serve to secure the pad to the flap upon each side of the center of the saddle, as shown.

The hook O, above the top of the saddle, is shaped, as shown, so that the greater the pull

of the checkrein upon the hook the more the rein will slip down toward the body of the hook, and thus be less likely to break the hook by having too great a pull thereon. The body 5 P of the hook extends backward under the flap and has the ring Q formed upon its rear end. Through this body are formed two sets of screw-holes, and through one set of these holes are passed the screws R. One of the screws 10 passes up into a tubular socket formed on the under side of the saddle S, while the other screw passes up into a socket, T, which is made separate from the saddle, but which passes down through it, as shown. In order to prevent 15 these two screws from working loose, the center of the pad has two screws, U, passed through it, and these screws U pass up into the other set of holes formed in the body of the hook, as shown, and thereby clamp the center 20 of the pad tightly against the under side of the saddle. As the pad bears tightly against the heads of the two screws R, it will be seen that they can never work loose. In case soft material—such as serge or cloth—for the pad 25 is used, these screws can be held in position by placing a light metallic plate against their heads and securing the plate in position by means of the screws U.

Having thus described my invention, I 30 claim—

1. In a harness-saddle, a flap or strap which extends entirely across the back of the animal, and which is provided with a lining at its center, in combination with the metallic plates C, 35 which are placed inside of the flap upon oppo-

site sides of the center, and which are secured in position by the staples D and the terrets I, the saddle being made flexible at its center, so as to conform to the shape of the back of the animal, substantially as shown. 40

2. The combination of the flap A, the hook O, provided with two sets of holes, with the saddle part S, provided with a screw-socket upon its under side to receive the screw R, and having an opening through which the 45 socket T is passed; so as to receive a second screw, R, the pad, and screws U, which are passed through the pad and the flap into the hook, substantially as described. 50

3. The combination of the flap, the hook having screw-holes made through its body, the saddle part, and the screws which secure the hook and saddle part upon opposite side of the flap, with the pad and the screws which pass through the pad into the body of the 55 hook, substantially as specified.

4. The combination of the flap, metallic plates placed therein, the staples provided with shoulders or stops, and prongs which pass down through the flap and the metallic 60 plates placed therein, and which are clinched on their under sides, the supporting-straps, and the rings connected thereto and to the staples, substantially as shown and described. 65

In testimony whereof I affix my signature in presence of two witnesses.

JOHN FISCHER.
